UNITED STATES PATENT OFFICE.

GEORGE BASLER, OF LYNN, MASSACHUSETTS.

FLEXING AND TEMPERING MACHINE FOR LEATHER SOLES AND THE LIKE.

1,184,916.

Specification of Letters Patent.

Patented May 30, 1916.

Application filed August 12, 1912. Serial No. 714,549.

To all whom it may concern:

Be it known that I, GEORGE BASLER, a citizen of the United States, and resident of Lynn, in the county of Essex and State of Massachusetts, have invented an Improvement in Flexing and Tempering Machines for Leather Soles and the like, of which the following description, in connection with the accompanying drawings, is a specification, like letters on the drawings representing like parts.

My present invention relates to apparatus for flexing and tempering leather stock more particularly shoe soles, the flexing being of a nature to stretch the fiber of the leather and open the pores thereof and the tempering being effected and completed by treating the soles to a copious application of a suitable tempering fluid preferably just before the flexing thereof whereby the tempering fluid strikes into the leather and permeates the fiber in a manner to render the same permanently flexible and pliable.

Apparatus of this general type is shown in my Patent No. 1,036,061 granted August 20, 1912, and the present case is in certain respects in the nature of improvements on the construction shown in said patent.

One prime object of the present case is to eliminate a large part of the endless belt conveyer system which in said patent is used to handle the soles throughout, and I preferably substitute for the portion of the belts extending past the liquid applying station and up to near the flexing station, a series of feed rollers adapted to convey and guide the soles to and past the fluid applying station where the liquid is automatically applied, and a succeeding pair of such rollers being adapted both to squeeze and remove the excess liquid from the soles, and mechanically promote the impregnation of the fiber with the liquid.

A further object of the invention is to make the entire machine more compact so that its feeding-in end and delivering end are close enough together so that a single operator can feed the soles in at one end and take them out at the other without changing his position.

A still further feature of the invention has to do with improved means for supplying the liquid to the soles in automatically controlled quantities, shutting off the liquid when there is no sole at the tempering station.

The above and other features and objects of the invention will be better understood from the following detailed description taken in connection with the accompanying drawings.

Referring to the drawings: Figure 1 is a side elevation of a machine wherein my invention is embodied; Fig. 2 is a plan view of the feeding-in end including the liquid supplying station; and Fig. 3 is a vertical section on line 3—3 of Fig. 2.

The feeding-in end of the machine is shown at the left in Fig. 1 and in further detail in the other figures, the soles or other stock pieces being fed between a lower power driven roll 1 and an upper roll 2 having its periphery corrugated or otherwise roughened to better grip the soles for drawing them in. The rolls 1 and 2 are mounted in suitable bearings in a frame work 3, the bearings of the roll 1 being stationary and those of the roll 2 being vertically slidable and normally pressed downward by springs 4 to cause the soles to be pressed between the rolls 1 and 2 and gripped for feeding especially by the roll 2. The roll 2 is shown as a little back from the roll 1 to locate the receiving mouth at a more convenient angle for the operator. From between the rolls 1, 2 the soles pass directly to a liquid applying station formed as a wide shallow trough or tray 5 mounted in position so that the soles are advanced over its adjacent edge along the guard and director piece 6 down into the trough or tank, being pressed down thereinto by spaced apart serrated disks 7 fixed on a shaft 8 which is mounted in vertically slidable bearings normally pressed downward by springs 9. The disks 7 are shown as three in number and the intermediate one is directly over a plate 10 pivoted at 11 to the tank bottom and engaged from beneath by the upwardly projecting stem 12 of a cone valve 13 normally pressed upward to its seat by a spring 14, the stem 12 in this position holding the plate 10 up a little distance above the bottom of the disk 7. The valve 13 controls the passage of tempering liquid through a pipe 15 to which it is delivered from any suitable pressure source and it will be understood that as a sole is fed between the disks 7 and the plate 10, the plate is forced down and the valve 13 pressed open to permit the delivery of tempering liquid to the trough and the sole therein, such supply being cut off at once

105
110

as soon as the sole has passed on its way out of the trough.

To insure a thorough and even wetting of all parts of the soles as they pass through the trough, its bottom which as seen in Fig. 6 is formed on an arc of gentle curvature, is provided at its respective sides with ribs 16, 17, the ribs 17 at one side alternating with the ribs 16 at the other side, so that each set 10 of ribs is opposite spaces at the other side of the trough. This keeps the soles up from the bottom of the trough so that the liquid can effectively contact therewith to impregnate the same and it insures an impregnation 15 of all parts of the leather surface in the passage through the trough. It will be observed that the director and guard plate 6 extends in from the trough at a proper angle not only to guide the soles in 20 between the disks 7 and through the bottom of the trough, but being up at some little angle from the bottom of the trough, it serves also as a guard to prevent the splashing out of liquid from this side of the 25 trough as the soles enter. The trough or tank 5 is preferably provided with a suitable overflow outlet 18 to prevent more than the proper amount of liquid accumulating in the tank for effectively wetting up the 30 "grain" side of the soles which as fed in are downward, the excess of liquid flowing down to a receptacle 19 beneath, this receptacle being shown as provided with sloping walls 20 at its outer side adapted to catch 35 drip from other parts of the tempering station. From the tempering station thus provided the soles pass upward and forward to be caught between upper and lower rolls 21, 22 preferably of felt or like material 40 mounted on shafts 23, 24 respectively, the shaft 24 for the lower roll being mounted in stationary bearings and the shaft 23 for the upper roll being mounted in vertically 45 slideable bearings normally pressed downward by the springs 25 so that the soles are pressed between these rolls. It will be observed that the roll 21 is a little forward of vertical alinement with the lower roll 22, the purpose of this being to effect a better 50 "bite" or grip of the rolls on the soles. The felt rolls 21, 22 between which the soles are thus strongly pressed serve to squeeze out the excess liquid and also promote the even and effective impregnation of the fiber by 55 the liquid in a manner that will be readily understood. From between the rolls 21, 22 the soles advance to an adjacent receiving mouth 26 formed between an upper belt 27 and a lower belt 28 which pass around adjacent rollers 29, 30 arranged to form such mouth to receive the soles and coöperate with other parts of the belt system to hold the belts strongly pressed together through 60 a part of their path of movement. From the 65 rolls 29, 30 the belts 27, 28 pass downward

and forward around a relatively small flexing roll 31 mounted on a shaft 32 and bending around the same at a sharp angle, they pass thence upward and backward around another somewhat larger flexing roll 33 70 fixed on a shaft 34. From this roll the belts continue to move together in parallelism for a short distance to the delivery point 35 where the upper belt passes up over a tension roller 36 having its bearings normally 75 pressed out to hold the belt under proper tension by springs 37 with adjustable backings 38. Thence the upper belt passes around a return roller 39 and past an intermediate adjustably mounted guiding roll 40 80 back to the roll 29 to complete its cycle of movement. From the delivery point 35 the lower belt passes around a roll 41 and an intermediate adjustably mounted roll 42 to a tensioning roll 43 mounted in like manner 85 as the roll 36 and thence back around the roll 30 to complete its cycle of movement. Thus as the soles enter the receiving mouth 26 between the held together belt portions, they are strongly and evenly gripped on all 90 portions of their surfaces by the belts and advanced around the flexing roll 31 which flexes them strongly and evenly from the lower side, which it will be remembered is the grain side and the side which has been 95 treated with the tempering liquid. Thence the soles still strongly and evenly pressed between the belts pass up around the upper reverse flexing roll 33 where they are flexed in the reverse direction. This upper flexing 100 roll which it will be understood tends to compress the grain side of the leather and open and stretch the pores of the other side, is considerably larger than the roll 31 for the reason that this reverse flexing if carried 105 to too great a degree would tend to crumple and wrinkle the grain side of the stock in an objectionable manner.

Power for operating the several parts of the conveying system thus provided may be 110 imparted in any suitable manner; as shown the shaft 34 is the prime driving shaft having fixed thereon a belt pulley 44 which drives the lower roll shaft 32 by spur gearing 45 fixed on the respective shafts. It also 115 drives the roll shaft 24 by means of sprocket wheels on the respective shafts engaged by sprocket chains 46. The shaft 24 in turn as shown drives the shaft 8 by means of a sprocket chain 47 engaging sprocket wheels 120 on the respective shafts, this chain being shown as guided around a lower idler sprocket wheel 48 and also passing at its forward reach around a sprocket wheel fixed 125 on the forward shaft 49 which carries the roll 1; the shaft of the upper roll 2 being shown as in driven engagement by spur wheels 50 on the respective shafts.

Among the marked advantages of my improved machine I would emphasize the fact 130

that the flexing belts are kept from getting soaked or wetted to any considerable extent by the tempering liquid, as the soles are fed into and past the liquid applying station by 5 the rollers described, the last set of which pressing upon the soles with felt or like surfaces squeeze the excess liquid out of the soles after the manner of a wringer, along with their action of mechanically promoting 10 the impregnation of the fiber by the liquid. This means of protecting the belts from becoming soaked is important, since when they become wetted to any considerable extent, they are apt to stretch and do not properly 15 cling to the rolls, and further are apt to rust the rolls and convey the liquid around to the various bearings with consequent injury thereto. The present machine also insures an adequate and effective application of the 20 tempering liquid by reason of the relatively wide shallow tank or trough through which the soles are progressed, in connection with the special ribbed bottom of such tank, whereby the contacting of the liquid with all 25 parts of the leather surface is insured. The belts in my improved machine being much shorter than in the machine of my said patent and with no long stretches, do not have to be as strong and perfect as before, 30 and have a much greater period of effective serviceability. It is to be further noted that the roller arrangement shown for feeding in the soles and moving them past the fluid applying station in connection with the belt 35 arrangement for flexing, makes the whole machine much shorter and more compact than before, and by reason of this it is quite practicable to have the feeding-in end and the delivering end of the machine close 40 enough together so that a single operator can, with one hand feed in the soles, and with the other remove them without changing his position.

I do not desire to be limited to the precise 45 constructional details shown, as I am aware that these can be varied to a considerable ex-

tent without departing from the spirit of the invention, and I therefore refer to the appended claims rather than to the foregoing 50 illustrative description to indicate the scope of my invention.

Having described my invention, what I claim as new and desire to secure by Letters Patent is:

1. A machine of the kind described, comprising a fluid applying station formed as a relatively wide shallow trough, a liquid supply thereto having a downwardly opening valve with a presser plate movable in the bottom of said trough with connection to 60 open said valve, means for directing stock pieces through said trough into contact with said plate, and means arranged to receive the stock pieces from said fluid applying station and bend them about an arc of small 65 radius while held strongly and evenly pressed upon the surfaces thereof.

2. A machine of the kind described, comprising a fluid applying station formed as a relatively wide shallow trough, a liquid 70 supply connection thereto having a downwardly opening valve, a presser piece movable in the bottom of said trough with connection to open said valve, and means for feeding stock pieces through said trough and 75 into yielding contact with said presser piece.

3. A machine of the kind described, comprising a fluid applying station formed as a relatively wide shallow trough, and means for feeding stock pieces through said trough, 80 said trough having ribs formed in two sets, a set at the receiving side of the trough alternating with a set at the delivering side thereof.

In testimony whereof, I have signed my 85 name to this specification, in the presence of two subscribing witnesses.

GEORGE BASLER.
